UNITED STATES PATENT OFFICE.

HAROLD NEIL PALMER, OF JACKSON, MICHIGAN, ASSIGNEE OF ONE-HALF TO
ROBERT C. ENOS, OF GRAND RAPIDS, MICHIGAN.

TANK-INDICATOR.

1,106,106.

Specification of Letters Patent.

Patented Aug. 4, 1914.

Application filed August 5, 1913. Serial No. 783,090.

To all whom it may concern:

Be it known that I, HAROLD NEIL PALMER, a citizen of the United States, residing at Jackson, Michigan, have invented certain new and useful Improvements in Tank-Indicators, of which the following is a specification.

This invention relates to improvements in tank indicators.

10 The main objects of this invention are to provide an improved indicator or gage and alarm for tanks such as the fuel tanks of motor vehicles, which is efficient and one which is at the same time very simple and economical to produce and durable in use, and one which is not likely to get out of repair while in use.

Further objects, and objects relating to structural details, will definitely appear 20 from the detailed description to follow.

I accomplish the objects of my invention by the devices and means described in the following specification.

25 The invention is clearly defined and pointed out in the claims.

A structure which is a preferred embodiment of my invention is clearly illustrated in the accompanying drawing forming a part of this specification, in which:

30 Figure I is a side elevation of a structure embodying the features of my invention, an automobile being indicated in outline in order to illustrate an approved method of installing the same. Fig. II is a front elevation of my improved indicator or gage, the reservoir connecting tube or pipe being broken away. Fig. III is a detail vertical section on a line corresponding to line 3-3 of Fig. II, the spiral shaft being shown in elevation. Fig. IV is a plan view of my improved indicator or gage, a source of electrical supply, as a battery, and an alarm bell being shown in conventional form in connection therewith. Fig. V is a detail horizontal section on a line corresponding to line 45 5-5 of Fig. III, a section of the automobile dash being shown. Fig. VI is a detail front view of the parts shown in Fig. V. Fig. VII is a horizontal section on a line corresponding to line 7-7 of Fig. III, showing details of the float. Fig. VIII is a horizontal section on a line corresponding to line 8-8 of Fig. III, showing further details of the float. Fig. IX is a side elevation of the index member or wheel 3. Fig. X is a front

55 elevation of a modified structure, the automatic alarm feature of the preferred construction being omitted. Fig. XI is a detail vertical section on a line corresponding to line 11-11 of Fig. X.

In the drawings similar reference characters refer to similar parts throughout the several views, and the sectional views are taken looking in the direction of the little arrows at the ends of the section lines.

60 Referring to the drawing, my improved indicator comprises a tube 1 which is preferably rectangular in cross section, as illustrated. At its upper end, the tube 1 is provided with a housing or casing 2 for the index member 3. The bottom 4 of the tube is provided with a connecting nipple 5 for the pipe 6, the pipe leading to the reservoir or tank 7.

65 In Fig. I, I show the preferred installation of my improved indicator, the indicator being arranged so that it is readable through the dash 8 of the vehicle.

70 The casing 2 is provided with a top plate 9 of insulating material. The upper end of the shaft 10 extends through the plate 9, which constitutes a bearing for the shaft, which is provided with a spiral or screw, and further provided with a pivot 11 at its lower end having a bearing in the bottom 4 of the tube. A support and bearing 12 is provided 75 for the shaft at the upper end of the tube.

75 The casing 2 is provided with a window 13 at one side through which the indicia on the index member 3 may be read. The indicator is mounted so that this window is on the inside of the dash as shown in Figs. V and VI. The index member 3 is preferably a sheet metal stamping having a rim 14 for the indicia.

80 Within the tube 1 is a float 15 of suitable material provided with a top plate 16 and a bottom plate 17. These plates have fingers 18 at the corners, which engage the corners of the tube, constituting sliding guide 100 members supporting the float against rotative movement. The top plate 16 has a slot 19 which engages the spiral or screw of the shaft so that, as the float rises and falls, it being supported against rotative movement, the shaft is rotated. The body of the float and the lower plate are provided with a round hole so that the shaft is free to turn therein.

85 On the upper end of the shaft is a contact 105

member 20 having a brush 21 coating with the contact plate 22. This contact plate is provided with a binding post 23 for the circuit wire 24 leading to the bell 25. A second 5 circuit contact member 26' in the form of a binding post is mounted in plate 9. The arm-like contact member 20 on the shaft swings against this post as the shaft is rotated, thus completing the circuit through 10 the contact members and the circuit wires 24 and 26 and the battery 27 to the bell. The contact member 20 is preferably provided with a spring 28 which swings against the post 26'.

15 In the modified construction shown in Figs. X and XI, the electric alarm feature is omitted, the shaft being provided with a pivot bearing 29 at its upper end engaging the top wall 30 of the index member 20 casing. The operation of this structure is the same as that of the main structure described,—that is, the rising and falling of the float rotates the index member, bringing the index member indicia thereon to view 25 through the window 13.

My improved indicator and alarm is very simple in structure and at the same time is durable in use and not likely to get out of repair.

30 I have illustrated and described simple embodiments with and without the electrical alarm feature. I have not attempted to illustrate or describe various modifications which I contemplate as I believe the disclosure 35 made will enable those skilled in the art to which this invention relates to adapt or embody the same as circumstances or conditions may require. I desire, however, to be understood as claiming my improvements specifically in the form illustrated as well as broadly within the scope of the appended 40 claims.

Having thus described my invention, what I claim as new and desire to secure by Letters Patent is:

1. In an indicator, the combination of a tube rectangular in cross section; an index member casing on the upper end of said tube having a window at one side; a top plate of insulating material for said casing; a spiral shaft arranged with its upper end extending through said top plate and having a bearing 50 therein, the lower end of the shaft being provided with a bearing pivot having a bearing in the bottom of said tube; a shaft bearing member at the upper end of said tube; an index member having a rim provided with indicia and mounted on said shaft within said casing; a contact plate mounted on said 55 top plate and provided with a binding post; a contact arm on said shaft provided with a brush coating with said contact plate; a contact member mounted on said top plate with which said arm engages as the shaft revolves, an electric circuit including said contact plate, 60 said contact member and a source of current supply, and a float on said shaft, said float being held against rotative movement whereby the shaft is rotated as the float rises and falls.

contact plate, said contact member and a source of current supply, and a float comprising a body portion and top and bottom plates having projecting corner lugs engaging the corners of the tube, one of said plates being slotted to engage the spiral shaft, whereby the shaft is rotated as the float rises and falls.

2. In an indicator, the combination of a tube rectangular in cross section; an index member casing on the upper end of said tube having a window at one side; a top plate of insulating material for said casing; a spiral shaft arranged with its upper end extending through said top plate and having a bearing therein, the lower end of the shaft being provided with a bearing pivot having a bearing in the bottom of said tube; an index member having a rim provided with indicia and mounted on said shaft within said casing; a contact plate mounted on said top plate and provided with a binding post; a contact arm on said shaft provided with a brush coating with said contact plate; a contact member mounted on said top plate with which said arm engages as the shaft revolves, an electric circuit including said contact plate, 75 said contact member and a source of current supply, and a float comprising a body portion and top and bottom plates having projecting corner lugs engaging the corners of the tube, one of said plates being slotted to engage the spiral shaft, whereby the shaft is rotated as the float rises and falls.

3. In an indicator, the combination of a tube; an index member casing on the upper end of said tube having a window at one side; a top plate of insulating material for said casing; a spiral shaft arranged with its upper end extending through said top plate and having a bearing therein, the lower end of the shaft being provided with a bearing pivot having a bearing in the bottom of said tube; a shaft bearing member at the upper end of said tube; an index member provided with indicia on its periphery and mounted on said shaft within said casing; a contact plate mounted on said top plate and provided with a binding post; a contact arm on said shaft provided with a brush coating with said contact plate; a contact member mounted on said top plate with which said arm engages as the shaft revolves, an electric circuit including said contact plate, 100 said contact member and a source of current supply, and a float on said shaft, said float being held against rotative movement whereby the shaft is rotated as the float rises and falls.

4. In an indicator, the combination of a tube; an index member casing on the upper end of said tube having a window at one side; a top plate of insulating material for said casing; a spiral shaft arranged with its upper end extending through said top 105 plate and having a bearing therein, the lower end of the shaft being provided with a bearing pivot having a bearing in the bottom of said tube; a shaft bearing member at the upper end of said tube; an index member provided with indicia on its periphery and mounted on said shaft within said casing; a contact plate mounted on said top plate and provided with a binding post; a contact arm on said shaft provided with a brush coating with said contact plate; a contact member mounted on said top plate with which said arm engages as the shaft revolves, an electric circuit including said contact plate, 110 said contact member and a source of current supply, and a float on said shaft, said float being held against rotative movement whereby the shaft is rotated as the float rises and falls.

plate and having a bearing therein, the lower end of the shaft being provided with a bearing pivot having a bearing in the bottom of said tube; an index member provided 5 with indicia on its periphery and mounted on said shaft within said casing; a contact plate mounted on said top plate and provided with a binding post; a contact arm on said shaft provided with a brush coating 10 with said contact plate; a contact member mounted on said top plate with which said arm engages as the shaft revolves, an electric circuit including said contact plate, said contact member and a source of current 15 supply, and a float on said shaft, said float being held against rotative movement whereby the shaft is rotated as the float rises and falls.

5. In an indicator, the combination of 20 a tube; an index member casing on the upper end of said tube having a window at one side; a top plate of insulating material for said casing; a spiral shaft arranged with its upper end extending through 25 said top plate and having a bearing therein, the lower end of the shaft being provided with a bearing pivot having a bearing in the bottom of said tube; a shaft bearing member at the upper end of said tube; an index 30 member provided with indicia on its periphery and mounted on said shaft within said casing; a pair of contact members on said top plate; a contact arm on said shaft coating with said contact members on said 35 plate; an electric circuit including said contact members and a source of current supply; and a float on said shaft, said float being held against rotative movement whereby the shaft is rotated as the float rises and falls.

40 6. In an indicator, the combination of a tube; an index member casing on the upper end of said tube having a window at one side; a top plate of insulating material for said casing; a spiral shaft arranged with its 45 upper end extending through said top plate and having a bearing therein, the lower end of the shaft being provided with a bearing pivot having a bearing in the bottom of said tube; an index member provided with indicia on its periphery and mounted on said 50 shaft within said casing; a pair of contact members on said top plate; a contact arm on said shaft coating with said contact members on said plate; an electric circuit including said contact members and a source of current supply; and a float on said shaft, said float being held against rotative movement whereby the shaft is rotated as the float rises and falls.

current supply; and a float on said shaft, said float being held against rotative movement whereby the shaft is rotated as the float rises and falls.

7. In an indicator, the combination of a 60 tube; an index member casing on the upper end of said tube provided with a window; a top plate of insulating material for said casing; a spiral shaft arranged with its upper end extending through said top plate; an index member provided with indicia and mounted on said shaft within said casing; a pair of contact members on said top plate; a contact arm on said shaft coating with said contact members on said top plate; an electric circuit including said contact members and a source of current supply; and a float on said shaft, said float being held against rotative movement whereby the shaft is rotated as the float rises and falls. 75

8. In an indicator, the combination of a tube rectangular in cross section; an index member casing on the upper end of said tube having a window at one side; a spiral shaft disposed longitudinally of said tube and projecting into said casing; an index member having a rim provided with indicia and mounted on said shaft within said casing; and a float comprising a body portion and top and bottom plates having projecting 80 corner lugs engaging the corners of the tube, one of said plates being slotted to engage the spiral shaft, whereby the shaft is rotated as the float rises and falls. 85

9. In an indicator, the combination of a 90 tube rectangular in cross section; an index member casing on the upper end of said tube provided with a window; a spiral shaft disposed longitudinally of said tube and projecting into said casing; an index member 95 provided with indicia mounted on said shaft within said casing; and a float comprising a body portion and top and bottom plates having projecting corner lugs engaging the corners of the tube, one of said plates being slotted to engage the spiral shaft, whereby the shaft is rotated as the float rises and falls. 100

In witness whereof, I have hereunto set my hand and seal in the presence of two witnesses. 105
